TAPE FOR ADJUSTABLE FASTENERS

Leo Roseman, Newark, N. J., assignor to Prime Fastener Company, Newark, N. J., a corporation of New Jersey

Application October 27, 1942, Serial No. 463,450

12 Claims.

(Cl. 24—206)

This invention relates in general to adjustable fasteners of the type wherein a hook is attached to one of two parts to be connected and cooperates selectively with any of a plurality of fastener elements attached to the other of said parts. Such fasteners are used for various purposes, for example to connect the edges of openings in garments such as brassières, girdles, aprons, etc., or for connecting any two parts of a garment or article.

Fasteners of this type often include a single row of fastener elements for example eyelets, cross-pieces, metal bars or the like secured to a fabric tape or body strip, to cooperate with a single hook that is attached to another tab or part, and sometimes two of such tapes are stitched together by a line of zig-zag stitches along the longitudinal edges of the tapes to form a double tape for use with two hooks on another part such that each row of fastener elements may cooperate with one hook.

Known fastener tapes of this character are not entirely satisfactory. Either they are not strong enough to withstand the tensional forces normally exerted upon them during use in for example a garment, or they are too complicated and expensive, or they are excessively bulky or stiff. In making fasteners which comprise two tapes stitched together, difficulty is encountered in aligning the corresponding fastener elements of the two rows, and the stitching frequently puckers one or both tapes so that the fastener elements are not regularly and accurately spaced apart in their rows, which causes improper register or engagement of the hooks with the fastener elements with consequent hindrance to the user in attempting to connect the hooks to the fastener elements, as well as uneven distribution of strains on the fastener during use thereof. The cost of double-tape fasteners of this type is more than twice the cost of the single tape fastener.

Therefore one object of my invention is to provide a fastener of the general character described which shall include novel and improved features of construction such that the fastener tape shall be simple, durable, flexible and thin and flat to ensure minimum of bulk.

Another object is to provide a double fastener tape, i. e., a tape having two rows of fastener elements, which shall be so constructed that the necessity for sewing two single tapes together shall be avoided, the corresponding fastener elements in the two rows of fastener elements can be easily and accurately aligned to properly engage cooperating hooks, and the tape can be produced con-

tinuously yard after yard rapidly and at relatively low cost.

It is essential that fastener tapes of this character shall have sufficient inherent stiffness to remain flat without collapsing, wrinkling or folding so as to facilitate connecting of hooks to the fastener elements, and at the same time shall be flexible so as, for example, to conform to the body when the fastener is used in a garment. In prior 10 fastener tapes of this type, those properties have been attained by strips of reenforcing material attached to and extending longitudinally of the body strips, generally between plies of the latter, and such reenforcing strips generally are required 15 also to ensure firm anchorage of the fastener elements on the body strip. Tapes so constructed not only are costly, but the reenforcing strips make the tapes bulky and consequently difficult to hem at their ends; and too much time is required to dry the tapes after laundering.

Therefore, another object of my invention is to provide a fastener tape of the general character described which shall embody novel and improved features of construction such that extra 20 reenforcing strips for the body strips shall be unnecessary, and the fastener elements themselves shall serve as reinforcements to stiffen and strengthen the body strip, whereby the tapes shall have minimum bulk and shall be inexpensive and 25 strong.

More particularly my invention contemplates a fastener tape of this character which shall comprise a body strip of fabric and a plurality of narrow cross-strips of fabric extending transversely 30 of the body strip in parallel relation to each other and means for securing said cross-strip to said body strip such that each cross-strip shall serve as two fastener elements, shall ensure accurate location of said fastener elements in alignment with 35 each other transversely of the tape so that the hooks will properly engage them and shall also reinforce and stiffen the body strip, and the tape shall be capable of withstanding heavy strains imposed upon said cross-strips by the cooperating 40 hooks during use of the fastener. Such tape is especially desirable at this time for the additional reason that no metal is required which results in a saving of metal for the war effort.

With many known adjustable fasteners of the 45 type that includes a part comprising a tape having two parallel rows of fastener elements, and another part having two hooks, one for each row of fastener elements, the fastener elements are arranged in pairs spaced longitudinally of the 50 tape and with one element of each pair in each

row; and due to the manner of spacing the fastener elements and the hooks, there may be unintentional simultaneous engagement of the hooks with fastener elements of different pairs, which causes the part that carries the hook to be thrown out of line with or in diagonal or twisted relation to the fastener tape. This is objectionable especially when the fastener is embodied in a garment such as a brassière where the fastener is obscured for example at the back of the wearer while being hooked.

Accordingly a further object of my invention is to provide an adjustable fastener which shall be constructed in a novel and improved manner to overcome such disadvantages of known adjustable fasteners and to ensure accurate and easy engagement of the hooks with the fastener elements at all times.

Other objects, advantages and results of the invention will be brought out by the following description in conjunction with the accompanying drawing in which

Figure 1 is a rear elevational view of a brassière having applied thereto an adjustable fastener.

Figure 2 is a composite view on an enlarged scale showing one section of the fastener in plan and the other section in perspective.

Figure 3 is a further enlarged fragmentary vertical longitudinal sectional view on the line 3—3 of Figure 1, and

Figure 4 is an enlarged transverse vertical sectional view on the line 4—4 of Figure 2.

In its broader aspects my fastener comprises two sections A and B one of which includes one or more rows of fastener elements C with which selectively cooperates the other section B of the fastener which includes a hook 12 for each row of fastener elements. While the invention contemplates the application of the fastener element C and the hooks 12 directly to two parts to be connected, for example two parts of a garment or article, the invention more particularly is directed to a fastener wherein the fastener elements are connected to a tape or strip 1, which is applied to a portion of a garment or an article such as one end of a brassière D, and the hooks 12 are attached to a tab or strip 2 which is connected to the other portion of the garment or article, such as the other end of the brassière D.

More specifically describing the invention, the part A of the fastener includes the body or base strip 1 of suitable material, for example textile fabric that has its longitudinal edge portions folded inwardly upon the same side of the strip as at 3.

Each fastener element C comprises a cross strip or bar of suitable material such as textile fabric that is disposed transversely of the base strip and secured thereto with portions of the cross strip spaced from the base strip to receive the bill of a hook and permit engagement of such hook with the cross strip.

In the embodiment of the invention illustrated, there are two rows of fastener elements C on the section A, each row including a plurality of fastener elements spaced longitudinally of the base strip 1. One fastener element in each row is in alignment transversely of the base strip with one fastener element in the other row so as to comprise a pair of fastener elements, and the elements of each pair are formed by the same cross strip. Preferably there are a plurality of cross strips 4 extending transversely of the base strip 1 in parallel relation to each other and spaced longitudinally of the base strip, and the extrem-

ities of the cross strips are located beneath the inwardly folded longitudinal edge portions 3 of the base strip as clearly shown in Figures 2 and 4.

Suitable means is provided for securing the end portions of the cross strips to the base strip and as shown lines of stitches 5 extend longitudinally of the base strip and transversely of said cross strips, each penetrating one inwardly folded edge portion 3, the main portion of the base strip and the cross strips 4.

A top strip 6 of suitable material such as textile fabric, extends longitudinally of the base strip and traverses the cross strips 4 intermediate their ends, the longitudinal edges of the top strip 6 being spaced from the edges of the inwardly folded portions 3 so as to expose portions of the cross strips 4 between them. Suitable means is provided for securing the top strip 6 and the cross strips 4 to the base strip A at points spaced inwardly from the lines of stitches 5 and as shown such means comprises lines of stitches 7 each extending longitudinally of the top strip adjacent one edge thereof and transversely of the cross strips and penetrating the top strip, the cross strips and the base strip. It is desirable that the lines of stitches 5 and 7 include a plurality of superposed stitches 8 at the points where said lines traverse the cross strips 4, so that the cross strips are firmly secured to the base strip. The spaces between the edges of the top strip 6 and the inwardly folded edge portions B form a channel to guide and receive the hooks as the latter are connected to the cross strips. Each line of stitches 5 and the adjacent line of stitches 7 traverse the cross strips or bars 4 and form a plurality of independent pockets of which said cross strips constitute the sides arranged one behind the other with their openings transverse of the strip and adapted to be engaged by a hook 12, the openings of the pockets being arranged in a direction transverse to the direction of pull of the hook on the cross strip.

Preferably each cross strip 4 comprises a plurality of plies of material stitched together, and as shown, each cross strip is formed of a single piece of textile fabric having its longitudinal edge portions folded inwardly as at 9 and brought into superimposed relation to each other by a fold 10 in the strip that extends along the longitudinal median line thereof. Lines of stitches 11 extending longitudinally of the strip secure the several plies together. The cross strips 4 thus are relatively stiff and strong so as to reinforce the base strip against unintentional folding or wrinkling, which is especially desirable where the fastener is used on a garment such as a brassière.

Now referring to the section B of the fastener, there is one hook 12 for each row of fastener elements C, each hook including a base 13 secured to the strip 2 in any suitable manner, and a bill 14 which projects from the strip so that it may be inserted beneath one of the cross strips 4 for connection thereto as shown in Figure 3. Preferably the cross strip 4 is of a width equal to or greater than the length of the hook bill 14 so that the hook will be prevented from swinging in planes perpendicular to the plane of the base strip and also to ensure adequate snug frictional contact of the hook with the cross strip and base strip to prevent accidental slipping or disconnection of the hook from the cross strip.

In accordance with the invention the bills of the hooks are spaced apart on the strip 2 a distance equal to that between the longitudinal median lines X—X of the rows of fastener ele-

ments, and the pairs of fastener elements C are spaced apart longitudinally of the base strip distances substantially greater than the distances between said longitudinal median lines of said rows of fastener elements. With such a construction it is impossible for one hook to be connected to one fastener element of one pair and the other hook to be connected to one fastener of another pair in such a manner as to cause the section B to be thrown out of line with or in diagonal or twisted relation to the section A. In other words, the structure will ensure that when one hook 12 engages one fastener element of a pair, the other hook will simultaneously engage the other fastener element of the same pair so that the two sections will be connected in exact longitudinal alignment with each other.

It will be observed that the base strip is severable between the cross strips 4 and that with the base strip constructed as shown and described, the extremity of the strip may be folded inwardly and hemmed without difficulty as indicated at 15. Also the whole tape or section A is flat, of minimum bulk, flexible and at the same time sufficiently stiff to prevent unintentional folding or wrinkling thereof.

Utilization of a single cross strip 4 for forming the two fastener elements of a pair overcomes the difficulty heretofore encountered in obtaining and maintaining alignment of the fastener elements of one row with corresponding elements of the other row transversely of the base strip in double fastener tapes of this type. Moreover, by forming the base strip of one piece of material and each cross strip of a single piece of material, the difficulty heretofore encountered in stitching together two tapes each having a single row of fastener elements is obviated. Furthermore, my fastener tape A can be easily manufactured on automatic machines at relatively low cost, and great strength and durability with a minimum of material and labor in constructing the tape, are obtained.

While I have shown the section A provided with a plurality of fastener elements C arranged in two parallel rows so that the hooks may selectively engage any of the pairs of fastener elements, it will be understood that the section A may have only a single fastener element or one pair of fastener elements and that the section B would in such cases have a single hook 12 or a pair of hooks respectively.

What I claim is:

1. An adjustable fastener part comprising a base strip having its longitudinal edge portions folded inwardly at the same side of the strip, and at least one cross-strip disposed transversely of said base strip, and stitches securing said cross-strip to said base strip with the extremities of said cross-strip located beneath said inwardly folded edge portions of said base strip so that a pocket is provided between said base strip and said cross-strip to permit engagement of a hook with said cross-strip.

2. The adjustable fastener part set forth in claim 1 wherein said base strip is formed of textile fabric and said cross-strip comprises a plurality of superposed plies of textile fabric stitched together.

3. An adjustable fastener part comprising a base strip, and a plurality of cross-strips disposed transversely and spaced longitudinally of said base strip, and lines of stitches running longitudinally of said base strip and transversely of said cross-strips and securing said cross-strips to the

base strip with a portion of each cross strip between lines of stitches spaced from said base strip to receive the bill of a hook and permit engagement of such hook with said cross-strip.

4. An adjustable fastener part comprising a base strip, and a plurality of cross-strips disposed transversely and spaced longitudinally of said base strip, a top strip running longitudinally of said base strip and traversing said cross-strip intermediate their ends, lines of stitches running longitudinally of said base strip and said top strip and penetrating them and said cross strips to secure the latter to said base strip, and fastening means for securing cross-strips to said base at points spaced from said lines of stitches so that the portions of each cross-strip between said longitudinal lines of stitches and said fastening means are spaced from said base strip to receive the bill of a hook and permit engagement of such hook with said portion of the cross-strip.

5. The adjustable fastener part described in claim 4 wherein the longitudinal edge portions of said base strip are folded inwardly over the extremities of said cross-strips, and the last-mentioned means comprises a line of stitches running longitudinally of said base strip through the latter, each inwardly folded edge portion and said cross-strips.

6. The adjustable fastener part set forth in claim 4 in which said base strip, and said top strip are formed of textile fabric and each cross-strip comprises a plurality of plies of textile fabric stitched together, and wherein the longitudinal edge portions of said base strip are folded inwardly over the extremities of said cross strips, and the last-mentioned means comprises a line of stitches running longitudinally of said base strip through the latter, each inwardly folded edge portion and said cross-strips.

7. An adjustable fastener comprising a part including a tape having two spaced parallel rows of fastener elements extending longitudinally thereof, and another part having two hooks, one for each row of fastener elements, said hooks being spaced on the corresponding part a distance equal to that between the longitudinal median lines of said row of fastener elements, said fastener elements being arranged in parallel pairs extending transversely of the tape with one element of each pair in each of said rows, and said pairs of fastener elements being spaced apart distances substantially greater than the distances between said longitudinal median lines of said rows of fastener elements.

8. A unitary fastening device comprising a strip of fabric, parts disposed transversely thereof, transversely spaced rows of stitching extending longitudinally entirely across said parts to provide a plurality of spaced apart pockets independent of each other with separable portions between them and arranged one behind the other with their openings transverse thereto and adapted to be alternatively engaged by co-operating means.

9. A fastening device for incorporation in a garment comprising a strip of fabric adapted to be secured to one part of a garment; a plurality of bars of fabric secured transversely to said strip of fabric by rows of stitching extending entirely across the strip so as to form a plurality of independent pockets of which the bars constitute the sides arranged one behind the other with their openings transverse to said strip and adapted to be alternatively engaged by cooperating means on another part of said garment that is to be con-

nected to the first said part, said bars being spaced apart and the strip being severable between the bars.

10. A fastening device for a garment comprising a plurality of initially separate bars of fabric arranged in parallel relationship secured by rows of stitching extending entirely across the strip to one part of a garment so as to form a plurality of pockets of which the bars constitute the sides arranged one behind the other and adapted to be alternatively engaged by cooperating means on another part of said garment that is to be connected to the first said part, the openings of said pockets being arranged in a direction transverse to the direction of pull.

11. A garment having one of its main body walls constituting a fastening device comprising a strip of fabric secured to one part thereof; a plurality of pockets associated with said strip arranged one

behind the other with their openings transverse thereto to coact with engaging means associated with another part of said garment that is to be connected to the first said part, adapted to engage said pockets alternatively so as to adjust the size of the garment.

12. As an article of manufacture a base strip having its longitudinal edges folded inwardly at the same side of the strip, a plurality of cross strips disposed transversely and spaced longitudinally of said base strip with the extremities thereof located beneath said inwardly folded edge portions of the base strip, and lines of stitches running longitudinally of said base strip and transversely of said cross strips and penetrating said inwardly folded edge portions and the main portion of the base strip and the cross strips.

LEO ROSEMAN.
